Patented Sept. 17, 1918.

Samuel Jankelson Inventor
By his Attorney
Max. Goldmann

UNITED STATES PATENT OFFICE.

SAMUEL JANKELSON, OF ROCKAWAY BEACH, NEW YORK, ASSIGNOR TO INCANDESCENT SUPPLY COMPANY, OF NEW YORK, N. Y.

DESIGN FOR A LAMP-SHELL BODY.

52,452.

Specification for Design.

Patented Sept. 17, 1918.

Application filed February 9, 1918. Serial No. 216,347. Term of patent 3½ years.

To all whom it may concern:

Be it known that I, SAMUEL JANKELSON, a citizen of the United States, residing at Rockaway Beach, Long Island, in the county of Queens and State of New York, have invented a new, original, and ornamental Design for a Lamp-Shell Body, of which the following is a specification, reference being

had to the accompanying drawing, forming part thereof.

The figure is a perspective view of a lamp shell body showing my new design.

I claim:

The ornamental design for a lamp shell body as shown.

SAMUEL JANKELSON.
